SOUNDING BOARD FOR RADIO RECEIVING SETS AND PHONOGRAHS.

Application filed April 23, 1925. Serial No. 25,269.

This invention relates to improvements in sounding boards for sound producing devices.

Heretofore it has been customary in photographs and radio receiving sets to cause a diaphragm to be vibrated to produce the audible sounds. These diaphragms are invariably small and formed of thin sheet material, such as metal in the case of an ear 10 phone or loud speaker, or mica and similar materials in the case of a phonograph. It has been well recognized that by employing a diaphragm in sound producing or reproducing devices, the diaphragm produces 15 a distortion of the sound vibrations, so that there is an effect of noise in conjunction with the tones produced by the diaphragm.

An object of this invention is to employ a sounding board as a diaphragm and also 20 as a sounding board in sound producing devices so that such distortion is eliminated.

With the foregoing and other objects in view which will be made manifest in the following detailed description and specifically pointed out in the appended claims, reference is had to the accompanying drawings for an illustrative embodiment of the invention, wherein:

Figure 1 is a top plan view, parts being 30 broken away and shown in section, illustrating a combined phonograph and radio receiving set to which my improved sounding board has been applied,

Fig. 2 is a vertical section taken substantially on the line 2-2 of Fig. 1, showing the phonograph as being operated,

Fig. 3 is a view similar to Fig. 2 showing the radio receiving set as being employed, and

Fig. 4 is a perspective view showing a modified form of sounding board.

Referring to the accompanying drawings wherein similar reference characters designate similar parts throughout, it will be 45 understood that the phonograph and radio receiving set illustrated upon the drawings are employed for illustrative purposes only, and that any suitable type of phonograph or radio receiving set or other device can 50 be employed for mechanically transmitting sound vibrations to the sounding board of my improved construction. On the drawings I have shown a container 10 which may

be supported upon legs 11. A bracket 12 is mounted within the container, and a suitable link 13 is pivotally supported upon the bracket 12 and serves to pivotally suspend the sounding board of my improved construction so as to permit its free vibration.

My improved sounding board consists of a 60 central board 14 preferably formed of good grain wood, but it is possible to form the board out of other materials. Upon the sides of the board there are positioned two pieces of sheet material, indicated at 15 and 16 respectively. In the modifications shown in Figs. 1, 2 and 3, these pieces of material are tapered in form, and are somewhat curved. They have their converging edges 65 constituting the top and bottom edges secured to the board 14 and their intermediate portions are disposed in spaced relation to the board. Only the converging edges are secured to the board so that the air pockets or sound amplifying chambers 17, defined 70 between the pieces of sheet material 15 and 16 and the board 14, are open at each end. I preferably form in the board 14 opposite the pieces of sheet material 15 and 16 one or more F holes 18, as I find that best 75 results are obtained by forming one or more apertures in the board 14 opposite the pieces of sheet material.

The phonograph which I have shown upon the drawing consists of a motor, generally designated at 19, which may be of any conventional construction and which is adapted to rotate a plate 20 arranged upon the top of the container 10. A record 21 is shown as positioned upon the plate, and is 80 engaged by a needle or stylus 22 which is mounted upon an arm 23. The arm 23 is rotatably mounted upon the upper end of a stem 24 which is fastened to the board 14 as by a suitable connection 25. It will be 85 noted that the position of the suspended link 13 is so arranged that the weight at the rear end of the board is sufficient to cause the stylus 22 to bear upon the top surface of the record 21. At the bottom of the board I have shown a needle 26 mounted on the board which is adapted to transmit 90 sound vibrations from the unit 27 of a radio receiving set. In order to contact the needle 26 with the unit 27, the arm 23 is lifted 100 and swung clear of the record 21 and the 105

plate 20, so that the board may be slightly lowered, bringing the needle 26 into contact with the radio unit 27.

The operation of the device is as follows: 5 If the phonograph is being operated, the sound vibrations which are produced upon the needle 22 by moving the record 21 beneath it are transmitted through the arm 23, the stem 24 and the connecting means 10 25 to the board 14. Because of the fact that the board 14 is freely suspended, these sound vibrations can freely influence the board, so as to vibrate it throughout its area and produce the sound. Although the board when 15 influenced by the sound vibrations will produce an audible sound, this sound is not of a sufficient magnitude for ordinary purposes unless the board is of a considerable size. In order to reduce the size, I arrange 20 the semi-confined air pockets near the board, which air pockets or sound amplifying chambers are formed by the pieces of sheet material 15 and 16. By use of the air pockets the sound is sufficiently amplified so that a 25 small board can be used. The pieces of sheet material 15 and 16 define the air pockets 17 upon both sides of the board 14, and in this manner the vibration of the board 14 produces an audible sound because 30 of the amplification produced by the air pockets. As previously stated, these air pockets are open at each end, so that the megaphone effect of producing harsh sounds is eliminated. As illustrated in Figs. 1, 2 35 and 3, the pieces of sheet material 15 and 16 are tapered, so as to tend to direct the sound produced in a given direction, namely, toward their large or widened end.

By this construction it will be appreciated 40 that no diaphragm is employed upon the arm 23 and that the board 14 serves not only as a diaphragm, but as a sounding board, and in this manner the distortion of the sound waves is greatly eliminated. Furthermore, 45 the orchestration of a pipe organ, a band or an orchestra, in which a plurality of different notes are simultaneously produced, is perfectly reproduced by the sounding board 14 without the distortion accompanied by the use of a diaphragm.

When the radio receiving set is employed, 50 it will be understood that it is unnecessary to use a diaphragm in the ear phones or loud speaker device which may constitute the unit 27, but it is merely necessary to transfer or create mechanical sound vibrations upon the needle 26, which vibrations are transmitted by the needle to the board and the board is vibrated in the same manner as by the phonograph.

In the modifications shown in Figs. 1, 2 and 3, the pieces of sheet material are preferably formed of paper, although they may be formed of other material, such as veneer 65 or a thin sheet of wood, if desired.

In the modification shown in Fig. 4, the improved sounding board consists of a central board 14^a having two pieces of sheet material 15^a and 16^a secured upon its sides. These pieces of sheet material are shown as 70 rectangular in form, having their top and bottom edges secured to the board 14^a and having their center portions disposed in spaced relation to the board, defining air pockets 17^a upon both sides of the board. 75 Suitable apertures or F holes 18^a may be formed in the board 14^a, which are similar to the apertures or F holes 18 in the board shown in Figs. 1, 2 and 3. The pieces of sheet material 15^a and 16^a in the modification shown in Fig. 4 are preferably formed of a thin layer of wood, such as veneer, although they may be formed of other material, if so desired.

From the above it will be appreciated 85 that an improved construction in sound producing or reproducing devices is provided, which eliminates the use of a diaphragm and consequently the distortion produced by the diaphragm, so that a clear and undistorted tone or a plurality of tones is produced by the device.

It will be understood that various changes in the detail of construction may be made without departing from the spirit or scope 95 of the invention as defined by the appended claims.

I claim:

1. A device of the character described comprising a support, a sounding board of wood freely suspended from the support for vibration throughout its area at audible frequency, a stylus mounted on the support and engaging the sounding board for vibrating the latter, means for reproducing and transmitting sound vibrations to the stylus, and tapered sheet material upon the side of the board with its medial portion spaced from the board to form a sound amplifying chamber, the converging sides of the sheet material being fixed to the board with the ends of the sheet material spaced from the board to form open ends for the sound amplifying chamber, and there being an aperture in the board opposite the sound amplifying chamber. 110

2. A device of the character described comprising a support, a sounding board freely suspended from the support for vibration throughout its area, a stylus mounted independently of the board and engaging the board for vibrating it at audible frequency, means for reproducing and transmitting sound vibrations to the stylus, and sheet material upon the side of the board with edges 120 of the sheet material fixed to the board and the medial portion of the sheet material spaced from the board to form a sound amplifying chamber.

3. A device of the character described com- 125

prising a support, a sounding board freely suspended from the support for vibration throughout its area at audible frequency, a stylus engaging the board for vibrating the latter, means for reproducing and transmitting sound vibrations to the stylus, and means mounted on the board defining an open ended sound amplifying chamber at the side of the board.

10 4. A device of the character described comprising a support, a sounding board freely suspended from the support for vibration throughout its area at audible frequency, a stylus engaging the board for vibrating the same, means for reproducing and transmitting sound vibration to the stylus, and means mounted on the side of the board defining a sound amplifying chamber at the side of the board.

15 5. A device of the character described comprising a support, a sounding board freely suspended from the support for vibration

throughout its area at audible frequency, a stylus for vibrating the board, means for reproducing and transmitting sound vibrations to the stylus, and means mounted on the side of the board defining a sound amplifying chamber at the side of the board, there being an aperture in the board opposite the sound amplifying chamber.

20 6. A device of the character described comprising a support, a sounding board freely suspended from the support for vibration throughout its area at audible frequency, a stylus for vibrating the board, means for reproducing and transmitting sound vibrations to the stylus, and tapered sheet material upon the side of the board with its converging sides fixed to the board and its medial portion spaced from the board to form a sound amplifying chamber.

25 In testimony whereof I have signed my name to this specification.

30 35 40 GEORGE C. LINDSEY.
